UNITED STATES PATENT OFFICE

JAMES M. PACKER, OF COLORADO SPRINGS, COLORADO, ASSIGNOR TO F. O. SCHOEDINGER, OF COLUMBUS, OHIO

RADIANT GAS HEATER

Application filed January 30, 1930. Serial No. 424,705.

This invention relates to gas heaters of the type known as "radiant" heaters, and has for its primary object to improve the construction and efficiency of heaters of this character.

It is another object of the invention to embody in a radiant type of gas heater novel and improved means for utilizing to the fullest extent the heat developed by the combustion of the fuel and to control the delivery of the developed heat into surrounding room areas where the heat may be used to the best advantage.

One form of the present invention is disclosed in the accompanying drawings, wherein:

Figure 1 is an elevational view of a stove constructed in accordance with the present invention,

Figure 2 is a vertical cross-sectional view taken through the stove or heater on the line 2-2 of Figure 1,

Figure 3 is a detail vertical sectional view taken through the upper part of the heater on the plane indicated by the line 3-3 of Figure 2,

Figure 4 is a transverse horizontal sectional view on the plane indicated by the line 4-4 of Figure 1, and

Figure 5 is a detail sectional view on the line 5-5 of Figure 2.

Referring more particularly to the drawings, the numeral 1 designates the metallic base of the heater, the corners of the heater being provided with vertically arranged legs 2 which are arranged to engage with a suitable supporting floor and to hold the heater in spaced relation from the floor. Arranged within the base is a longitudinally

extending gas manifold 3 with which connect a plurality of burner members 4, the upper portions of which are flanged to engage with the hearth plate 5 of the base. The base in this instance is provided with upstanding side walls 6, which are formed with horizontally extending ribs 7 which are adapted to be received within grooves 8 formed in the sides 9 of a clay backing 10.

In the preferred form of my invention this backing is of integral formation, and is

formed from clay or other suitable refractory material. In addition to the sides 9 the backing 10 includes a rear wall 11 and an overhanging dome portion 12, the latter being integrally formed with the upper part of the rear wall 11 and with the upper portion of the side walls 9. By this construction the backing provides a radiant receiving chamber 13.

Mounted upon each of the burner members 4 and arranged within the chamber 13 are vertically disposed relatively spaced inner and outer radiant sections or elements 14 and 15 respectively. The inner elements 14 each consist of a tubular clay body reduced at its lower end to provide a projection 16 which engages with the axial portion of the co-operating burner head 4. The elements 14 are of substantially uniform diameter throughout their length, but their upper ends are outwardly flared or circularly enlarged as at 17 in order to engage with the inner cylindrical walls of the outer sleeve-like elements 15. These outer elements are also formed from clay and act as protecting jackets for the inner elements, in that the inner elements are completely received within said sleeve-like outer elements and supported in an operating position thereby. The outer elements or sleeves are perforated as at 18 to admit of the free escape of the heat developed by the combustion of gases in the annular combustion spaces formed between the adjacent walls of the elements 14 and 15. This combustion of gases results in highly heating the surfaces of the elements 14 and 15 until the latter obtain a luminous or glowing condition, with the result that the heater delivers into the room area a large percentage of radiant heat.

The principal feature of the present invention, however, resides in the construction of the dome 12. This dome includes, immediately over the radiants 14 and 15, an enlarged combustion chamber 19 which, in effect, constitutes a portion or the upper part of the chamber 13, with the exception that the chamber 19 is provided with a closed forward wall formed by an outward-

ly and downwardly projecting lip 20. Extending longitudinally and centrally of the chamber 19 is a vertically extending web 21, which has its under edge provided with a groove 22, adapted for the reception of the centering projections 23 provided on the upper end of the outer radiant elements 15. The web 21 is provided at intervals with transverse slots 24 which are adapted to receive the projections 23 during the operation of applying or removing the elements 14 and 15 with respect to their operating positions in the heater. The rear wall 11 of the backing is provided with a centrally disposed flue outlet 25, which is disposed contiguous to the upper end of the elements 14 and 15 and communicates with the chamber 19 at the rear side of the web 21.

Having now described my invention in detail I will now endeavor to point out the more important advantages thereof. In heaters of this character considerable difficulty has been encountered in effectively heating the radiant elements throughout their full height. Under ordinary conditions these elements become highly heated contiguous to their lower portion or adjacent to the burner corresponding to the members 4. This partial heating of the radiant elements is largely due to the fact that the developed heat is allowed to pass too quickly to the flue or stack outlet, or is not properly directed upon the radiant elements throughout their length. In the present invention whole heating of the radiant elements throughout their height is assured by the construction of the dome portion 12 and the provision of the chamber 19 formed therein and the relationship which the surfaces of said chamber bear to the upper portion of the radiant elements. In the operation of the stove the heat developed by the combustion of gases between the elements 14 and 15 passes outwardly and upwardly. A large proportion of this heat is trapped or confined in the dome chamber 19 and is reflected back from the walls of this chamber upon the upper portions of the radiant elements, instead of being allowed to pass without use to the stack outlet as is the case in customary design. This arrangement provides a very efficient gas heater of the radiant employing type.

While I have shown and described the preferred embodiment of my invention, it will be understood that changes may be made in the details of construction without departing from the spirit of the invention or scope of the appended claims.

What is claimed is:

1. In a gas heater, a base frame, a backing of refractory material positioned upon said base frame, said backing being formed to include spaced vertical side walls, a ver-

tical rear wall and a forwardly projecting overhanging top wall, the outer portion of said top wall being provided with a downwardly projecting lip shaped to produce a trapping chamber in the upper portion of the backing, said back wall being provided with a gas outlet communicating in part with said chamber, a web depending from the under surface of said top wall and extending longitudinally of said chamber between said lip and said opening and dividing said chamber into a pair of compartments, burner members carried by said base frame, and vertically disposed radiant elements positioned within the confines of said backing and arranged in registration with said burner members, the upper ends of said radiant elements at their axial portions engaging the under surface of said web.

2. In a gas heater, a base frame, a backing of refractory material positioned on said base frame, said backing being formed to include spaced vertical side walls, a vertical rear wall and a forwardly projecting overhanging top wall, the outer portion of said top wall being provided with a downwardly projecting lip shaped to produce a trapping chamber in the upper portion of the backing, said back wall being provided with a gas outlet communicating in part with said chamber, a longitudinally extending web formed with restricted openings therein depending from the under surface of said top wall and positioned between said lip and said opening and dividing said chamber into a pair of compartments, burner members carried by said base frame and vertically disposed radiant elements positioned within the confines of said backing and arranged in registration with said burner member, the upper ends of said radiant elements engaging the lower edge of said web.

3. In a gas heater, a base frame, a backing of refractory material positioned on said base frame, said backing being formed to comprise spaced vertical side walls, a vertical back wall and a forwardly and outwardly projecting top wall, the under surface of said top wall being shaped to provide a longitudinally extending chamber, burner members carried by said base frame, vertically disposed radiant elements positioned within the confines of said backing and arranged in registration with said burner members, and a longitudinally extending web depending from the under surface of said top wall and dividing said chamber into a pair of compartments, the lower edge of said web being in approximately the same horizontal plane as the outer edge of said top wall and in engagement with the upper ends of said radiant elements.

4. In a gas heater, a base frame, burner members carried by said base frame, vertically disposed radiant elements arranged

in registration with said burner members, a backing of refractory material positioned upon said base frame and surrounding said radiant elements, said backing being formed to comprise spaced vertical side walls, a vertical back wall and a forwardly and outwardly projecting top wall, said top wall having its under surface formed to provide a longitudinally extending chamber, and a centrally disposed downwardly projecting web extending longitudinally of said chamber and dividing said chamber into a pair of longitudinally extending compartments, said web engaging the upper ends of said radiant elements.

5. In a gas heater, a base frame, burner members carried by said base frame, vertically disposed radiant elements arranged in registration with said burner members, a backing of refractory material positioned upon said frame and surrounding said radiant elements, said backing being formed to comprise spaced vertical side walls, a vertical back wall and a forwardly and outwardly projecting top wall, the outer portion of said top wall being provided with a downwardly projecting lip shaped to produce a chamber in the upper portion of the backing, the lower edge of said lip being spaced from and in the same horizontal plane as the upper ends of said radiant elements, and a downwardly projecting web extending longitudinally of said chamber and engaging the upper ends of said radiant elements, said web dividing said chamber into a pair of compartments.

In testimony whereof I affix my signature.
JAMES M. PACKER.
